Attorney

UNITED STATES PATENT OFFICE.

SEVERIN A. WATNEY, OF NORTHWOOD, IOWA.

COVER RETAINER.

Application filed October 9, 1925. Serial No. 61,528.

This invention relates to an improved article of manufacture which may be conveniently designated as a cover retainer, the same having more particular reference to a 5 novel contrivance which is adapted to be attached to a cigar box or the like for maintaining the cover in a vertical open position.

Broadly, the invention has reference to a device of this kind which is extensible to permit it to be adjusted to fit upon covers of different lengths, the same comprising attaching hooks or their equivalents to be connected with the cover adjacent its hinge connection with the box, together with an angular stop which is adapted to bear against the rear wall of the box in holding the cover in an open position, and to facilitate access to the contents of the box.

More specifically speaking, the invention 20 relates to a cover holding device of the kind designated, wherein the same comprises a pair of duplicate slides provided with hooks adapted to be connected with the cover, and a connecting plate between these slides, the 25 slides and the plates being bent to provide angularly disposed portions and being telescopically connected together.

Other objects and advantages will become 30 apparent from the following description and drawings. In the accompanying drawing forming a part of this application, and in which like numerals are employed to designate like parts throughout the same:—

Figure 1 is a front elevation of the cigar 35 box equipped with a lid or cover holding device constructed in accordance with the present invention.

Fig. 2 is an end elevation of Fig. 1.

Fig. 3 is a perspective view of one of the 40 slides and the connecting plates.

In carrying out the invention, I employ a retainer which is constructed of three pieces of metal. One piece is in the form of a central connecting plate 1, and the other two 45 are in the form of duplicate slides 2. The plate 1 is oblong in configuration and is bent between its longitudinal edges as at 3 to provide angularly disposed portions having the approximate angular relation indicated.

Each slide comprises a plate 4 of a width 50 greater than the plate 3, whereby to permit its longitudinal edges to be bent upon them-

selves to provide side channels 5, in which the aforesaid plate 1 is received. Formed integral with the outer end of the plate 4 is an 55 extension which is bent upon itself to form an attaching hook 6. As stated, there are two of these slides and these are slidably mounted upon the connecting plate 1, in the complete relation indicated in dotted lines in 60 Fig. 1.

In practice the hooks 6 of the two slides 2 are connected with the end edges of the cover 7 adjacent the hinged end of the latter. When the cover is swung to open position as 65 indicated in Fig. 2, the lower half of the retainer forms a stop which serves against the rear wall of the box 8. This allows the cover to be swung to and beyond said center and allowed to drop to bring the stop in engagement with the box and to maintain the 70 cover in that position.

By considering the description in connection with the drawings persons familiar with devices of this class will be able to obtain a 75 clear understanding of the invention. Therefore a lengthy description is thought unnecessary.

Minor changes coming within the field of invention claimed may be resorted to if desired. 80

Having thus described my invention, what I claim as new is:—

As a new article of manufacture, a 85 cover attachment for cigar boxes for maintaining the cover in a rearwardly inclined open position comprising a connecting plate and a pair of complementary slides, each slide comprising a plate having its longitudinal edges bent to form guide channels telescopically receiving the connecting plate, said connecting plate and slides being bent between their longitudinal edges to provide upper and lower angularly disposed portions, the upper portions being adapted to 90 rest against the box cover and the lower portions against the rear wall of the box when the cover is in an open position, said slides being provided at their outer ends with extensions bent to form cover engaging hooks, 95 said hooks being on the upper portions of the slides. 100

In testimony whereof I affix my signature.
SEVERIN A. WATNEY.
